CONDENSER

William W. Garstang, Indianapolis, Ind., assignor
to P. R. Mallory & Co., Incorporated, Indianapolis, Ind., a corporation of Indiana

Application August 22, 1932, Serial No. 629,808

9 Claims. (Cl. 175—315)

My invention relates to improvements in electric condensers and particularly to electrolytic condensers.

It is one of the objects of my invention to obtain greater capacity per unit of volume of condensers which have heretofore been used or manufactured.

Another object of my invention is to construct a condenser which may be readily and easily manufactured and due to the increase in capacity 10 may be accordingly made in much smaller sizes.

For the purpose of disclosing my invention I have illustrated certain embodiments thereof in the accompanying drawing in which:

Fig. 1 is a side elevation of a condenser embodying my invention;

Fig. 2 is a longitudinal sectional view of one form of structure embodying my invention;

Fig. 3 is a longitudinal sectional view of another form of my invention;

Fig. 4 is a longitudinal sectional view of still another form of my invention; and

Fig. 5 is a longitudinal sectional view of a further modification of my invention.

According to my invention as particularly illustrated in Fig. 1, the cathode and anode each preferably consists of a wire 1 and 2 wound in parallelism on a spool 3. In carrying out my invention as illustrated in Fig. 2 the anode preferably consists of aluminum wire having a coating of dielectric film coating the same which may be of aluminum oxide. The cathode may consist of a similar aluminum wire or of wire of other suitable material and this wire is preferably covered with absorbent material. This absorbent material may be in the form of a cotton covering braided or wound thereon in any desirable manner. According to the preferred commercial practice of constructing the condenser, anode and cathode wires are wound in side by side relation 30 continuously upon the spool, layer upon layer until the desired amount of wire has been rolled into spool form. The spool thus formed may then be immersed in an electrolyte of any of the well known kinds and is preferably triethanolamine borate. The condenser is allowed to remain immersed in the electrolyte until the absorbent covering for the cathode is thoroughly impregnated with the electrolyte. While this is the preferred 40 manner of constructing my condenser it will be understood that the absorbent covering for the cathode may be impregnated with the electrolyte before the wires are wound into spool form. In order to more quickly and more thoroughly impregnate the absorbent covering of the

cathode I may impregnate this covering under a vacuum or under pressure either when completely wound or before the wire is wound upon the spool. The cathodes and anodes may be connected by suitable leads in any desired manner to exterior apparatus.

In the structure illustrated in Fig. 3 the anode may consist of the wire wound in layers in spool form and having interposed between the layers a cathode 5 in the form of an aluminum or other suitable metal sheet or foil. Interposed between the layer of wire and the foil layer is a layer of absorbent material, such for instance as cotton gauze, or the like. In this structure the gauze may be impregnated with an electrolyte as described in connection with Fig. 2.

In Fig. 4 the structure is substantially the same as that illustrated in Fig. 3 with the exception that in Fig. 4 I have used a cotton covered wire thereby dispensing with the layer of cotton gauze.

In Fig. 5 I have illustrated a structure wherein the anode 6 consists of a wire spool and the cathode 7 may take the form of the container. In this structure I have dispensed with the gauze separator and have left between the outer periphery of the spool and the container a sufficient space to receive the electrolyte therebetween. Suitable coverings 8 and 9 may be used for closing the ends of the container and these closure members are preferably of insulating material and may be in the form of fiber discs.

The capacity of a condenser for any given voltage is in proportion to the surface area of the anode member or members. Due to the fact that in my condenser I use wire I am enabled to materially increase the surface area of the anode member or members without increasing the ultimate size of the condenser.

Furthermore the construction of the condenser is extremely simple particularly with respect to the structure illustrated in Fig. 1 as all that is necessary is to feed to a revolving spool or spindle a pair of wires, one of which is cotton covered and the other of which has had formed thereon a film as heretofore described. I am therefore enabled to construct a condenser at extremely low cost and provide a condenser of comparatively small size having a largely increased capacity.

While I have shown in the drawing the wire used as being substantially cylindrical in cross section, wire having other than cylindrical cross sectional shape may be used.

I claim as my invention:

1. A condenser including an anode and cathode consisting of wires wound concentrically and

separated by an absorbent spacer impregnated with an electrolyte.

2. A condenser in which the electrodes each comprises wires, the wires, at least one of which is film forming being wound concentrically and separated by an absorbent spacer impregnated with an electrolyte.

3. A condenser in which the electrodes, at least one of which is film-forming, comprise wires wound in parallel relation in concentric layers, at least one of said wires being covered by an absorbent material impregnated with an electrolyte.

4. As a new article of manufacture, a condenser comprising two wires, at least one of which is film forming, one of said wires being covered with absorbent material, wound in parallel relation into a coil structure and having the absorbent covering impregnated with an electrolyte.

5. A condenser comprising a cathode element and an anode element, one of said elements comprising a series of coils of film forming wire, the other element comprising a sheet, and an absorbent spacer interposed between said sheet and coils.

sorbent impregnated with an electrolyte interposed between said sheet and coils.

6. A condenser comprising a cathode and an anode, each comprising coils of wire arranged in proximity to one another and having interposed therebetween an absorbent spacer carrying an electrolyte.

7. A condenser including a pair of electrodes, at least one of which is film forming, each comprising coils of wire arranged in proximity to one another, the wire of at least one of said coils being covered with an absorbent material impregnated with an electrolyte.

8. A condenser including an anode element comprising a wire coil, a cathode element arranged adjacent the coils of said anode and an absorbent spacer carrying an electrolyte interposed between the cathode and anode element.

9. A condenser including an anode element comprising a wire coil, a cathode element arranged adjacent said anode element, the wire of said anode coil being covered with an absorbent material impregnated with an electrolyte.

WILLIAM W. GARSTANG.
